CLAIM

The ornamental design for a vehicle wheel rim, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front, top, right side perspective view of a vehicle wheel rim showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

Any portion of the design shown in the color yellow is for the purpose of illustrating portions of the vehicle wheel rim that form no part of the claimed design. The drawings include grayscale surface shading which illustrates contour, not any particular color.
